FENCE TOOL

Original Filed May 29, 1922

INVENTOR.

BY F. H. C. Graves.

J. H. Comer.
ATTORNEY.

UNITED STATES PATENT OFFICE.

FAY H. C. GRAVES, OF SPRINGFIELD, MASSACHUSETTS.

FENCE TOOL.

Application filed May 29, 1923, Serial No. 564,613. Renewed January 27, 1925.

To all whom it may concern:

Be it known that I, FAY H. C. GRAVES, a citizen of the United States, residing at Springfield, in the county of Hampden and

5 State of Massachusetts, have invented certain new and useful Improvements in Fence Tools, of which the following is a specification, reference being had to the accompanying drawing.

10 This invention refers to tools and more particularly to those adapted for use in connection with the proper installation of fencing or fence wires on posts, or devices to which such could be appropriately attached.

15 The invention has among its objects to provide such a tool with parts or a combination of parts that the work of attaching fences with staples to posts can be readily, 20 quickly and conveniently done, or to manipulate the ends of wires or other attachments used in the work, whereby they will afford a strong and tight means of tying in fences or fence wires or the like. Another object 25 is to have such a tool that it will not only have an effective action but also have a relatively great leverage that will eliminate all unnecessary looseness in the staples or wires used in connection with it. Another 30 object is to have the tool such that it may be used to undo its work effectively should such be required; and many other objects will become apparent as the invention is more fully set forth.

35 The use of fences is increasing in lines that seem to indicate the use of metal posts in preference to other kinds. Such posts are usually provided with small holes properly spaced and disposed so that when 40 staples are used in the holes and around the wires they will hold the fence wires. The use of the staples is customary, although other means are also used in certain cases.

The staples are however hard to install because the tools used for them do not bend the staples properly or require the use of several workmen or implements. This device takes the staples or wire end, and with a slight rotating action of the hand, bends 50 it over against the post where it securely presses against the same and in a resilient manner by reason of the peculiar bend it gives the staple.

The jaws 2 and 3, which may be termed 55 teeth, are placed adjacent to the end of the shank and are separated from each other

by the opening 4, and offset outwardly from the sides of the shank as indicated in the drawings, so as to be open to receive the staple legs.

60 The tool can be used in the reverse way for untying the staples or wire pieces or similar devices used for the purpose.

In the drawings which illustrate by way of example an embodiment of this invention:

70 Figure 1 is a view in perspective of a stapling tool and also a side elevation of a staple that has been operated upon and in position;

75 Fig. 2 is a view of the stapling tool ready to bend a staple end or leg; Fig. 3 is a view with the tool in a position after taking a ninety degrees movement, and Fig. 4 is a view of the tool after it has completed its movement and bent the staple leg completely over and in the form shown in Fig. 1;

Fig. 5 is a modified form of the tool having the jaws on one side of the tool;

80 Fig. 6 is another modified form with the jaws on both sides at one end;

Fig. 7 is another modified form having jaws on opposite ends and sides; and

85 Fig. 8 is another modified form using an offset handle such as might be required in certain cases.

Similar reference characters refer to similar parts throughout the drawings.

In the construction shown 1 represents the shank of the tool, and 2 an outer jaw, 90 and 3 an inner jaw at an end of the shank. A space or slot 4 is provided between the jaws and is sufficiently large to permit the insertion of the leg of a staple or the like. Jaws in the type shown in Fig. 1 are provided at both ends not only to afford a larger number of jaws but also to provide a stop that will prevent the tool slipping out of the hand while its other jaw end is being used on a staple.

100 The legs of the staples are shown at 6 and 7 with a connecting bend or hump 8 adapted to embrace a fence wire 9. The staple is inserted in the slot 10 of an iron fence post 11 over the wire 9, and the legs 105 brought out through on the other side of the iron. The jaw 2 is placed on the side of the leg of the staple to which it is desired to bend the latter. This places the slot 4 about the leg and the jaw 3 ready to press against it. The shank is then raised and the jaw 3 pressed against the leg. This 110

causes the leg to bend and rotate towards the face of the post. The rotation of the tool is continued until the leg is pressed over the jaw 2 and in the form shown in Fig. 1. 5 The result brings the leg down against the post face with a slight hump in rear of the point of the staple leg.

The operator then uses the tool similarly on the other leg of the staple, and the tie 10 of the fence wire is completed.

The various modifications appear self-explanatory, and use in general the same operations in their functioning. All the 15 jaws need not be of the same size but made to meet the requirements or various forms and sizes of wire and staples used.

While several forms of the invention have been shown in the drawings, it is not desired to limit this application for patent to 20 these particular forms nor in any other way, otherwise than limited by the prior art, as other constructions could be used that would employ the same principles and come within the scope of the appended claim.

What I claim is:—

25 A stapling tool of the class described, comprising a flat body of substantial uniform thickness and substantially rectangular in cross-section and with all its parts in substantially the same plane, said body having 30 adjacent its flat outer end a plurality of jaws spaced apart and offset equally from the same side of the body and in the plane thereof, said jaws being rectangular in cross-section and of the same width and 35 having inner and outer parallel edges perpendicular to the longitudinal axis of the body, which inner edges are suitably spaced apart, whereby the jaws are adapted to engage either or both legs of a staple to bend 40 it as desired when the tool is rotated on said end.

In testimony whereof I hereunto affix my signature in the presence of two witnesses.

FAY H. C. GRAVES.

Witnesses:

JOHN B. SHEA,
A. P. CONNOR.
